MOTOR COMPRESSOR

Raul Pateras Pescara, Paris, France

Application January 5, 1933, Serial No. 650,353
In Germany June 7, 1932

13 Claims. (Cl. 230—56)

My invention relates to motor compressors of the type including a pair of opposed pistons the inner ends of which reciprocate freely in a common central cylinder and the outer ends of which are adapted to reciprocate in two outer cylinders provided with suitable valves for compressing air or any other fluid into a reservoir. In motor compressors of that type a mixture of air and fuel is admitted into the central cylinder between the two pistons and caused to explode at the proper time so as to drive outwardly the two pistons. The inward stroke of said pistons takes place under the action of the cushions of air that remain in the dead spaces of the outer cylinders at the end of the outward or compression stroke.

One object of the present invention is to provide a compressor of that type with automatic regulating means for allowing air to escape from the outer cylinders during a portion of the outward stroke of the pistons, said means being suddenly brought into play as soon as the pressure in the reservoir reaches a certain value, so as to reduce or even bring to zero the output of the compressor, and being suddenly brought out of action when the pressure in the reservoir falls below a certain value.

Another object of my invention is to provide a compressor of that kind in which the correct return or inward stroke of the pistons is insured under all conditions of work.

A further object of my invention is to provide a compressor provided with the automatic regulating means above referred to in which the injection of fuel into the central cylinder is automatically regulated in accordance with the conditions of work of the machine.

Still further objects of my invention will appear from the following detailed description of a preferred embodiment of my invention with reference to the accompanying drawing, given merely by way of example, and in which:

Fig. 1 is a diagrammatic view showing in longitudinal section a motor compressor according to my invention; and,

Fig. 2 is a diagram illustrating the operation of the compressor.

As shown in Fig. 1, the inner ends of pistons 11 and 12 are adapted to reciprocate in central cylinder 13, while their outer ends are adapted to reciprocate in a fluid-tight manner in outer compressing cylinders 14 and 15 respectively. The movements of said pistons are synchronized through connecting rods 16 and cranks 18 adapted to rotate about the axis of shaft 17. The pis-

tons insure the distribution by uncovering inlet and outlet ports 19 and 20 controlled by suitably regulated valves 19a and 20a respectively. The fuel is injected into cylinder 13 by means of a pump 84.

The outer ends of cylinders 14 and 15 are connected with compressed air reservoir 25 through valves 23 and conduits 24. Cylinders 14 and 15 are further provided with outlet valves 72 and 73 fitted in recesses 70 and 71 and which are controlled through mechanisms that will be herein-after described.

The variations of the pressure in one of said cylinders 14, 15 according to the position of the piston in said cylinder are shown in the diagram of Fig. 2. The pressures are plotted in ordinates and the positions of the cylinder in abscissas. When the compressor is running under full load, valves 72 and 73 being closed, the diagram of pressures is N—O—P—Q and the energy for the return of the pistons is proportional to area I—P—Q. When the compressor is running idle, valves 72 and 73 are open and the compression in, say, cylinder 15, instead of starting from N, starts only when piston 12 has covered the whole of recess 71, that is to say from point Q of the diagram. The compression curve QP is substantially the same as the expansion curve PQ so that the energy for the return stroke of piston 12, which is proportional to area Q—P—I, is substantially the same in the case of the compressor running idle as in the case of the compressor running under full load.

Valves 72, 73 are controlled by rocking members 76, 77, which are actuated by two stops 79 and 80 carried by a sliding rod 78. The valves are brought back into their closed positions by return springs 74 and 75.

Rod 78 is actuated through a finger 93 by a lever 94 provided with a slide for said finger and pivoted about axis 95. Said lever is subjected to the action of a spring 96 the other end 97 of which is fixed to a sliding rod 98 integral with a piston 99 adapted to slide in a cylinder 102. One of the faces of said piston 99 is subjected to the air pressure in reservoir 25 through a tube 101 while the other face of said piston is subjected to the action of a spring 100 the strength of which is adjustable.

The output of pump 84 can be adjusted through a rod 85 controlled by a rocking member 86. Said rocking member is actuated by a rod 88 fixed to a piston 89 adapted to slide in a cylinder 90 one end of which is connected, through tube 92 with reservoir 25. One face of said piston 89 is there-

fore subjected to the pressure of the compressed air in said reservoir while the other face is subjected to the action of a spring 91 the strength of which is adjustable. Furthermore, a stop 87 carried by sliding rod 78 is adapted to actuate rocking member 86.

Rockshaft 17, which carries the eccentric 83 through which pump 84 is actuated is provided at its end with a slotted piece 104 which, only for certain positions of the slot, allows a stop 103 carried by sliding rod 78 to pass freely.

The operation of the device is as follows:

If there are but small variations of pressure in reservoir 25, regulation takes place through variation of the output of the injecting pump, which is controlled by the position of piston 89 in cylinder 88, through rod 86, rocking member 86 and rod 85.

On the contrary, if the pressure in reservoir 25 becomes so high that a correct return stroke of pistons 11 and 12 could no longer be insured, piston 89 moves a relatively great distance toward the left hand side and, due to the displacement of rod 86, spring 88 takes the position shown in dotted lines in the figure, thus causing lever 94 to swing toward the left hand side of the figure and to drive sliding rod 78 together with it. Stops 79 and 80 cause valves 72 and 73 to be opened and the compressor now runs idle. Simultaneously, stop 87, acting on rocking member 86, causes rod 85 to be brought into the position that insures the proper output of the pump for the new conditions of running.

It might be injurious to a good working of the motor compressor to open valves 72 and 73 at a time corresponding to certain positions of rockshaft 17, but owing to the presence of piece 104 provided with a slot adapted to allow the passing of stop 103 therethrough only when the rockshaft 40 is not in said positions, any danger from that direction is avoided.

Of course, if no margin of regulation is required when the compressor is running under full load, due to the stability of the motor compressor, control 88 can be dispensed with.

While I have described what I deem to be a practical and efficient embodiment of my invention, it should be well understood that I do not wish to be limited thereto as there might be changes made in the arrangement, disposition and form of the parts without departing from the principle of my invention as comprehended within the scope of the appended claims.

What I claim is:

1. A motor compressor of the type described, comprising in combination, a cylinder, a pair of opposed pistons adapted to reciprocate in said cylinder in opposite directions, means for admitting fuel and air into said cylinder between said pistons, two cylinders adapted to receive the outer ends of said pistons respectively, a storage reservoir for compressed air, check valves in the outer ends of said two cylinders for connecting them with said reservoir, means for admitting air into said cylinders during the inward stroke of the pistons, means for allowing air to escape from the last mentioned two cylinders during a portion of the outward stroke of the pistons, and means, sensitive to the air pressure in said reservoir, for controlling the last mentioned means.

2. A motor compressor of the type described, comprising in combination, a cylinder, a pair of opposed pistons adapted to reciprocate in said cylinder in opposite directions, means for admit-

ting fuel and air into said cylinder between said pistons, two cylinders adapted to receive the outer ends of said pistons respectively, a reservoir for the compressed air, check valves in the outer ends of the two last mentioned cylinders for connecting them with said reservoir, means for admitting air into the two last mentioned cylinders during the inward stroke of the pistons, means for allowing air to escape from the two last mentioned cylinders during a portion of the outward stroke of the pistons, means for controlling the amount of fuel admitted into the first mentioned cylinder, and means, sensitive to the air pressure in the reservoir, for controlling simultaneously the two last mentioned means.

3. A motor compressor of the type described, comprising in combination, a cylinder, a pair of opposed pistons adapted to reciprocate in said cylinder in opposite directions, means for admitting fuel and air into said cylinder between said two pistons, two cylinders adapted to receive the outer ends of said pistons respectively, a reservoir for the compressed air, check valves in the outer ends of the two last mentioned cylinders for connecting them with said reservoir, means for admitting air into the two last mentioned cylinders during the inward stroke of the pistons, at least one valve provided in the wall of each of the two last mentioned cylinders at an intermediate point of its length, elastic means for urging said valves in their closed positions, means, sensitive to the air pressure in said reservoir, for opening said valves when said air pressure rises above a given value and allowing them to be closed by said elastic means when said air pressure falls below a given value, and means, operatively connected with the last mentioned means, for reducing the amount of fuel admitted into the first mentioned cylinder when the valves are opened and increasing it when they are closed.

4. A motor compressor of the type described, comprising in combination, a cylinder, a pair of opposed pistons adapted to reciprocate in said cylinder in opposite directions, means for admitting air into said cylinder between said two pistons, a pump for injecting fuel into said cylinder between said pistons, two compression cylinders adapted to receive the outer ends of said pistons respectively, a reservoir for the compressed air, check valves in the outer ends of the two last mentioned cylinders for connecting them with said reservoir, means for admitting air into the two last mentioned cylinders during the inward stroke of the pistons, at least one valve provided in the wall of each of the two last mentioned cylinders at an intermediate point of its length, elastic means for urging said valves toward their closed positions, a cylinder, a piston in the last mentioned cylinder, a tube connecting one end of the last mentioned cylinder with said reservoir so as to push the last mentioned piston in one direction, a spring urging the last mentioned piston into the opposite direction, a tripping mechanism operatively connected with the last mentioned piston, means operated by said tripping mechanism for opening the last mentioned valves when the tripping mechanism is in one position and for allowing said last mentioned valves to be closed by said elastic means when the tripping mechanism is in the other position, and means actuated by said tripping mechanism for varying the feed of said pump.

5. A compressor according to claim 3 further comprising means, sensitive to the air pressure

in said reservoir, for varying the amount of fuel admitted into the first mentioned cylinder.

6. A compressor according to claim 4 further comprising means, sensitive to the air pressure in said reservoir, for varying the feed of said pump.

7. A compressor according to claim 4 further comprising a cylinder, a piston mounted in a fluidtight manner in the last mentioned cylinder, a tube connecting one end of the last mentioned cylinder with said reservoir so as to push the last mentioned piston in one direction, a spring urging the last mentioned piston into the opposite direction, and means operatively connected with the last mentioned piston for varying the feed of said pump.

8. A motor compressor of the type described, comprising in combination, a cylinder, a pair of opposed pistons adapted to reciprocate in said cylinder in opposite directions, means for admitting air into said cylinder between said two pistons, a pump for injecting fuel into said cylinder between said pistons, two compression cylinders adapted to receive the outer ends of said pistons respectively, a reservoir for the compressed air, check valves in the outer ends of the two last mentioned cylinders for connecting them with said reservoir, means for admitting air into the two last mentioned cylinders during the inward stroke of the pistons, at least one valve provided in the wall of each of the two last mentioned cylinders at an intermediate point of its length, elastic means for urging said valves toward their closed positions, a rocking member adapted to cooperate with each of the last mentioned valves for opening them, a sliding rod, stops carried by said rod and adapted to act on said rocking members respectively, a fourth cylinder, a piston in the last mentioned cylinder, a tube connecting one end of the last mentioned cylinder with said reservoir so as to push the last mentioned piston in one direction, a spring urging the last mentioned piston into the opposite direction, a tripping mechanism operatively connected with the last mentioned piston, means for operatively connecting said tripping mechanism with said sliding rod so that for one position of the tripping mechanism the rocking members are caused by the stops on the rod to open the last mentioned valves, while for the other position of the tripping mechanism they allow the valves to be closed by said elastic means, a rod for controlling the feed of said pump, a rocking member adapted to cooperate with the last mentioned pump, and a stop carried by the sliding rod for actuating the last mentioned rocking member.

9. A compressor according to claim 8 further comprising means, sensitive to the air pressure in said reservoir for varying the feed of the pump.

10. A compressor according to claim 8 further comprising a cylinder, a piston fitted in a fluidtight manner in the last mentioned cylinder, a tube connecting one end of the last mentioned cylinder with said reservoir so as to push the last mentioned piston in one direction, and means operatively connected with the last mentioned piston for acting on the last mentioned rocking member.

11. A motor compressor of the type described, comprising in combination, a cylinder, a piston adapted to reciprocate in said cylinder, means for admitting fuel and air into said cylinder, a second cylinder adapted to receive the outer end of said piston, a storage reservoir for compressed air, a check valve in the outer end of said second cylinder for connecting it with said reservoir, means for admitting air into said second cylinder during the inward stroke of the piston, means for allowing air to escape from the second cylinder during a portion of the outward stroke of the piston, and means adapted to control the last mentioned means in dependence on the output of the motor compressor.

12. A motor compressor of the type described, comprising in combination, a cylinder, a piston adapted to reciprocate in said cylinder, means for admitting fuel and air into said cylinder, a second cylinder adapted to receive the outer end of said piston, a storage reservoir for compressed air, a check valve in the outer end of said second cylinder for connecting it with said reservoir, means for admitting air into said second cylinder during the inward stroke of the piston, means for allowing air to escape from the second cylinder during a portion of the outward stroke of the piston, means adapted to control the last mentioned means in dependence on the output of the motor compressor, and means for controlling the amount of fuel admitted into the first mentioned cylinder.

13. A motor compressor of the type described, comprising in combination a cylinder, a piston adapted to reciprocate in said cylinder, means for admitting fuel and air into said cylinder, a second cylinder adapted to receive the outer end of said piston, a storage reservoir for compressed air, a check valve in the outer end of said second cylinder for connecting it with said reservoir, means for admitting air into said second cylinder during the inward stroke of the piston, means for allowing air to escape from the second cylinder during a portion of the outward stroke of the piston, and means sensitive to the air pressure in said reservoir, for controlling the last mentioned means.

RAUL PATERAS PESCARA.
